UNITED STATES PATENT OFFICE.

ALFRED L. RUTHVEN, OF BUFFALO, NEW YORK, ASSIGNOR TO SIMPLEX TRAIN CONTROL CO., INC., OF ROCHESTER, NEW YORK, A CORPORATION OF NEW YORK.

MEANS OF ELECTRICAL TRACK-CIRCUIT CONTROL.

1,372,457.

Specification of Letters Patent. Patented Mar. 22, 1921.

Application filed February 4, 1918. Serial No. 215,300.

To all whom it may concern:

Be it known that I, ALFRED L. RUTHVEN, a citizen of the United States, residing at Buffalo, in the county of Erie and State 5 of New York, have invented certain new and useful Improvements in Means of Electrical Track-Circuit Control, of which the following is a specification.

The present invention relates to rail road 10 block signaling and automatic train control, and aims to provide novel and improved means for coöperation between the train and track equipments for controlling the movement of the train under the various 15 conditions, such means eliminating the use of electrical, mechanical or other contact or similar devices between the train and track and thereby removing a serious objection to train controlling apparatus embodying such 20 devices.

It is the object of the invention to provide coöperating means between the train and track utilizing magnemotive force as the medium of control, to eliminate contact and 25 like devices heretofore used, which have serious objections impairing their efficiency.

Another object of the invention is the provision of means of the nature indicated employing novel mechanism to utilize the magnemotive force for purpose of control. 30

A further object is to provide such means constructed and arranged for automatically placing the train equipment in danger position when such track conditions exist, as 35 the train passes the controlling points, and for automatically clearing the apparatus should the danger be removed when the train passes a controlling point in clear condition, beyond those in danger condition.

40 A further object is the provision of the means of the character above indicated embodying electro-magnets and armatures, one set being movable to produce different conditions, such as clear and danger, and the other being movable in response to the aforesaid set so as to bring the train equipment to the proper condition according to the track equipment.

With the foregoing and other objects in 50 view, which will be apparent as the nature of the invention is better understood, the invention resides in the arrangement and combination of parts hereinafter described and claimed, it being understood that 55 changes within the scope of what is claimed

can be made without departing from the spirit of the invention.

The invention is illustrated in the accompanying drawings, wherein—

Figure 1 is a diagrammatical view of 60 the apparatus.

Fig. 2 is a perspective view of the brake valve operating device.

Fig. 3 is a vertical section on the line 3—3 of Fig. 1. 65

Fig. 4 is a perspective view of the track device, slightly modified in form.

Fig. 5 is a sectional detail of a modified means for operating the track device.

Fig. 6 is a diagrammatical view of the 70 track equipment showing the track devices of the present invention connected to the electrical circuits of a simple normal danger signal system.

Fig. 7 is an elevation showing a modified 75 form of the automatic controller for the pneumatic equipment.

Fig. 8 is a fragmental elevation thereof looking at right angles to the line of view 80 in Fig. 7.

The invention forming the subject matter of this application is preferably, although not necessarily, used with the pneumatic train equipment disclosed in my pending application for patent on combination automatic and manually operable air brake, power control and alarm system, filed June 15, 1917, Serial No. 175,018, it being understood, however, that the present improvements can be used for operating or controlling various train or vehicle equipments. In order that the operation of the apparatus can be better understood, the pneumatic equipment is shown in its simple form in 85 Figs. 1 and 2, and is here briefly described. 90 95

Pneumatic equipment.

The pneumatic equipment, forming the subject matter of the pending application above referred to, includes the main reservoir 100 1 for supplying the compressed air or pressure fluid, which is controlled as usual by the engineer's brake valve 2 having the handle 3 and usual exhaust port 4 direct to the atmosphere which is closed 105 when using this equipment. The equipment further includes an automatic controller 5 having the casing 6 in which a stem valve 7 is slidable, said valve having a piston 8 working in a cylinder 9 in said casing to 110

- provide means for operating said valve pneumatically. The valve 7 has a port 10 to normally establish communication between the pipe 11' and exhaust port 11 of the casing 6 leading to the atmosphere, the pipe 11' being connected to the brake valve 2 to receive the air discharged from the brake pipe when the brakes are applied as usual. The valve 7 in its normal position 10 is lowered so that the port 10 establishes communication between the pipe 11' and exhaust port 11, but when said valve is raised as shown in Fig. 1, the port 10 establishes communication between the pipe 11' 15 and the pipe 12 leading to a power interrupting means 13, which when the pressure fluid flows thereto, serves to interrupt the steam or other motive power which propels the vehicle or train.
- 20 The cylinder 9 is supplied with pressure fluid for raising and lowering the valve 7, by two conduits 14 and 15 connected to the lower and upper ends of the cylinder, and a main controlling valve 16 controls the flow 25 into said conduits alternately from the respective conduits 17 and 18 in communication with the respective supplementary reservoirs 19 and 20 in the casing 6. A pipe 21 connected to the main reservoir 1 supplies 30 the pressure fluid, and a port 22 in the valve 7 alternately establishes communication between the reservoirs 19 and 20 and said supply pipe, the pressure fluid flowing to the reservoir 19 when the valve 7 is 35 down and to the reservoir 20 when the valve is up. A centrifugal governor 23 is operable within the casing 6 and is connected to the valve 16, whereby the rotation of the governor will raise the valve 16, whereas when 40 the governor stops and gravitates it will lower the valve 16 which controls the movement of the valve 7 that in turn controls the power interrupting means 13 and other devices as will hereinafter appear. The 45 governor 23 is operated by one or more electrical motors 24 or their equivalents which are controlled by the present improvements. When the governor 23 is in operation and the valve 16 raised, pressure 50 fluid will flow from the reservoir 20 and conduit 18 into the conduit 15 and upper end of the cylinder 9 to move the piston 8 and valve 7, as seen in Fig. 1, thus producing danger indicating conditions. It will be 55 apparent that when pressure fluid flows from one of the reservoirs 19 and 20, it is supplied into the other since the valve 7 reverses when the valve 16 changes its position.
- 60 A brake valve operating device 25 is used for actuating the engineer's brake valve 2 beyond his control, and said device includes a casing 26 secured to the brake valve casting and having an oscillatory member 28 65 therein fitted on the stem 27 of the brake

valve which extends into the casing 26, the arrangement being such that when the member 28 turns in one direction it will operate brake valve 2 for applying the brakes, permitting the engineer to also so operate 70 the valve 2 if desirable or necessary, and when the member 28 turns in the other direction it operates the valve 2 for releasing the brakes. Pipes 29 and 30 connect the casing 26 with the casing 6, which has a conduit 32 communicating with the pipe 21 by the way of port 22 when the valve 7 is up. The valve 7 has a third port 31 establishing communication between the conduit 32 and pipe 29 when the valve 7 is 80 raised, whereby the pressure fluid will flow from the main reservoir to the device 25 for pneumatically and automatically operating the brake valve 2 to apply the brakes. The casing 6 has a third supplementary 85 reservoir 33 which is supplied with pressure fluid also from the conduit 32 and by way of the port 31 when the valve 7 is up, so that when said valve lowers, its port 31 will now establish communication between the reservoir 33 and pipe 30 in order that the pressure fluid from said reservoir flows to the device 25 for returning the member 28 and valve 2 to release the brakes.

A set of suitable signals 34 are operated 95 pneumatically by being connected by means of a pipe 35 with the conduit 32, so that said signals will operate when the brakes are applied.

Track device.

100

The track device as shown in Fig. 1, is located between the rails 36 of the track and is operated by the usual semaphore 37 having the operating mechanism 38, although as 105 hereinafter set forth, the track device can be operated otherwise by conditions of traffic. Said device includes a danger armature 39 and a pair of clearing armatures 40 all mounted for up and down movement on the 110 track and preferably elongated longitudinally thereof. As shown, the armature 39 is shorter than and arranged between the armatures 40 at the center of the track. A casing 41 of non-magnetic material incloses 115 said armatures to protect them from the weather conditions and to avoid injury thereto or tampering therewith, said casing being of non-magnetic material so that it will not interfere with the magnetic cooperation between the train and track devices. It will be noted that this casing 41, which covers the armatures or magnetic members on the track, has its ends inclined 120 to deflect stray objects over the casing, and the top of the casing is provided with longitudinal corrugations or depressions between the armatures and merging at their ends into the inclined ends of the casing, to stiffen the top which is thin so as to reduce 130

the clearance between the track and vehicle devices. The armatures 39 and 40 are carried by levers 42 fulcrumed within the casing 41, so that when the armature 39 is 5 raised to active position, the armatures 40 are lowered to inactive position, and vice versa. An arm 43 is connected to the levers 42 and is in turn connected by a rod 44 with the semaphore mechanism 38, although any 10 other suitable mechanical, electrical or equivalent connection can be used for raising and lowering the armatures according to the position of the semaphore. The armature 39 is sufficiently heavy to counterbalance the two armatures 40 so that said 15 armatures will move freely in response to their operating means. The rod or connection 44 between the track device and semaphore is preferably inclosed within a tubular housing 45 extending from the casing 41 to the semaphore casing.

Responsive train device.

A device carried by the train or vehicle is 25 responsive to the armatures 39 and 40 for controlling the pneumatic equipment above described, and thus bring said equipment to danger position when the armature 39 is up, or bring said equipment to clear position, 30 when the armatures 40 are raised. This train device includes a danger electro-magnet 46 movable over the armature 39 in either direction; a danger retaining electro-magnet 47 coöperable magnetically with one 35 rail 36 of the track or some other magnetic object adjacent which said magnet is located at all times; and a clearing electro-magnet 48 movable over one armature 40 or the other according to the direction of travel. 40 Since the armature 39 and magnet 46 are located at the center track, two armatures 40 at opposite sides of the armature 39 are used to take care of traffic in either direction, since the magnet 48 may be at either side of the 45 magnet 46. The magnets are inclosed within a protecting casing 49 of non-magnetic material to avoid interference with the magnetic fields. The casing 49 is shaped to conform to the magnets and deflect snow 50 and foreign objects to one side.

The magnets 46 and 47 operate in unison, and for this purpose, a rock shaft 50 is journaled in the casing 49 and has a crank 51 from which the magnet 46 is suspended by 55 means of a link or hanger 52. The shaft 50 has a second crank 53 from which the magnet 47 is suspended by means of a link or hanger 54, and the crank 53 is longer than the crank 51 in order that the magnet 47 will 60 have a greater vertical movement than the magnet 46. Thus, when the magnets 46 and 47 are in normally raised position, the magnet 46 will be within distance of the armature 39 when in raised position, to be attracted thereto when said magnet is ener-

gized, whereas the magnet 47 will be sufficiently removed from the rail 36 so as not to be attracted thereto even though energized. However, when the magnet 46 is attracted to the armature 39, as seen in Fig. 1, the shaft 70 50 in being rocked will bring the magnet 47 sufficiently close to the rail 36 or other magnetic object to be attracted thereto, and thereby retain both magnets in lowered position even after the magnet 46 has been carried away from the armature 39. In order to raise the magnets 46 and 47, an arm 55 is secured to the shaft 50 and has an adjustable weight 56 thereon, which by gravitating will turn the shaft 50 and raise the cranks 80 51 and 53 and therefore also raise the magnets suspended therefrom. The weights 56 can be so adjusted as to raise the magnets without a jar or jolt, and permit them to be attracted to their magnetic objects easily. 85 An electrical switch 58 is operated by the shaft 50, to control two circuits and alternately open and close them. A second rock shaft 57 is journaled in the casing 49 and has a crank 59 from which the clearing magnet 90 48 is suspended by means of a link or hanger 60, an arm 61 being secured to the shaft 57 and having an adjustable weight 62 thereon for raising the magnet 48, the same as the weight 56 raises its magnets. An electrical 95 switch 63 is operated by the shaft 57 to open and close an electrical circuit. The magnets 46, 47 and 48 with their coils move up and down longitudinally of their respective polar axes and are preferably of the inverted U-shape, in order that their fields will dip or extend downwardly a maximum distance from their poles, to assure of the attraction of the magnets to their armatures when they are raised, even though several 100 inches gap may be provided between the magnets and armatures in raised position. The armatures when lowered must be sufficiently removed from the fields of the magnets so as not to attract them. 110

An electrical generator 64 or other source of electrical energy is provided for operating the electrical motors 24 and for energizing the magnets 46, 47 and 48, and said generator 64 has the leads 65 extending to the 115 switches 58 and 62. The leads 66 of magnet 48 are connected to the switch 58 to be connected to the leads 65 when the switch 58 is in one position with the magnets 46 and 47 down, said circuit being opened when the 120 last named magnets are in raised position. The leads 67 of the magnets 46 and 47 are connected to both switches 58 and 63, said magnets being shown as connected in parallel, and the switch 62 when "on" with the 125 magnet 48 in raised position, will close the circuit between leads 65 and 67 so that the magnets 46 and 47 are energized either when up or down. The leads 68 of the controller 5, which supply the electrical energy 130

for operating the motors 24, are connected to the switch 58, which closes the circuit thereof when the magnets 46 and 47 are raised, and opens said circuit when said magnets 5 are lowered.

Operation.

Under normal operating conditions, the magnets 46, 47 and 48 are all in raised position, so that the switch 63 connects the leads 67 with the leads 65 of the generator, and magnets 46 and 47 are therefore normally energized. The switch 58 will disconnect the leads 66 of magnet 48 from the generator leads 65 when the magnets 46 and 47 are raised, but said switch 58 thereby connects the leads 68 with the energized leads 67 so that the motors 24 will operate under normal conditions and rotate the governor 23. This will raise the valve 16, whereby the valve 7 is in lowered position, the port 10 therefore permitting the pressure fluid to escape through the port 11 to the atmosphere in applying the brakes manually as usual. Now, should the responsive train device pass a controlling point of the track where the danger armature 39 is in raised position, with the semaphore 37 at danger, the magnet 46 in passing over the armature 39 will be instantly attracted thereto, thereby raising the weight 56, reversing the switch 58 and bringing the magnet 47 into attractive relation with the rail 36 or other magnet object, and said magnet in being attracted to said object will hold the switch 58 in its new position even after the magnet 46 has passed the armature 39. The magnet 47 thus serves to retain the danger position of the train device. The switch 58 will now close the circuit of magnet 48 so that it now becomes energized, but opens the circuit of the controller 5 so that the motors 24 stop, permitting the governor 23 to gravitate and lower the valve 16, which will result in the valve 7 being raised, so that the pressure fluid flows to the signals 34 to operate them, and also flows to the device 25 for automatically operating the brake valve 2 to apply the brakes, the discharging pressure fluid from the brake pipe, flowing by way of the pipes 11' and 12 to the power interrupting means 13, thereby also cutting off the power to bring the train to a halt. Thus, whenever the train passes a track device in danger position, the train will be stopped, and it is preferable to have the track devices normally in danger position to stop the train, unless the track device is first brought to clear position. Should the train proceed under caution conditions, that is, at a slow rate of speed, and pass the next track device which has been brought to clear position by the removal of the danger, the armatures 40 being raised and the armature 39 lowered, the

clearing magnet 48 in passing over one of the armatures 40 will be attracted thereto, thus opening switch 63 and the circuits of magnets 46 and 47. The magnets 46 and 47 will therefore become dead and will no longer hold the switch 58 in danger position, so that the weight 56 will return the magnets 46 and 47 and switch 58 to normal position. This will again close the circuit of the controller 5, so that it will restore clear conditions, and switch 58 in being returned will also open the circuit of magnet 48 so that it becomes dead and returns to normal position. The train can then proceed as before, due to the removal of danger.

Modifications.

Fig. 4 shows a slightly different form of casing 41' placed on the ties.

Fig. 5 illustrates a different way of operating the track device. Thus, the operating rod 44' can be connected to the core 44^b of a solenoid 44^a, which can be housed within an extension 45' of the casing 41. The track device can thus be operated electrically as well as mechanically as shown in Fig. 1. It is evident that although the armatures counterbalance one another, the clear armatures 40 move to inactive position and the danger armatures to active position, when the solenoid 44^a is deenergized, thereby assuring of the track device being at danger under all conditions, excepting when the system is operative for energizing said solenoid in clear conditions. If the system fails, danger conditions will prevail, and the same is true with the mechanical connection shown in Fig. 1.

Fig. 6 illustrates the solenoids 44^a of a number of track devices in the circuits of a simple normal danger signal system. As shown, the rails 36 are divided into the sections A, B, C, D, and E insulated from one another, and the semaphores 37 are located between the blocks, each of which contains two or more sections. As many track devices can be used as desired, and as shown they are placed at the junctures of the track sections and between the ends thereof. The signal system illustrated is of a well known simple form and includes an electro-magnet 70 connected to each pair of rail sections at one end and a track battery 71 connected thereto at the other end to complete a normally closed circuit for each section and maintain the magnet 70 energized. Each magnet 70 attracts and normally closes an armature switch 73 disposed in signal circuits 72 of the semaphores 37, and each of said circuits also includes an armature switch 74 attracted and normally opened by a magnet 70 in rear. Thus, taking one circuit 72, it includes the semaphore 37 between sections B and C, armature switches 73 at the ends of section C, armature switch 74 between sec-

tions A and B, and the magnets 44^a at the centers and forward ends of sections B and C. The normally open switch 74 opens the circuit, so that the respective semaphore and track device or armatures thereof are in normal danger position. This condition will also exist if sections C or D are occupied, because this will short circuit one of the magnets 70 of said sections to let the respective 5 switch 73 open, and the opening of the semaphore circuit at any one of the several points will produce danger conditions. However, should a train enter section B, moving toward the left in Fig. 6, the magnet 70 of 10 said section will be short circuited and therefore be deenergized, so that its switch 74 will close the circuit and thus move the semaphore and track devices to clear position whereby the train can advance past the 15 magnet 70. When the train enters section C, the magnet 70 thereof will be deenergized by the short circuit established, and even though switch 74 is again opened, as well as switch 73 between sections 20 B and C, a second normally opened switch 75 of the magnet 70 under discussion will be closed by the deenergization of said magnet 70, and thus close the circuit of the two magnets 44^a in advance, so that the train can 25 pass the respective track devices. Switch 75 forms a short circuit between the battery 76 of the circuit 72, and the semaphore 37 and magnets 44^a in rear, so that a train following in section B will be stopped because 30 said semaphore and last mentioned magnets 44^a will be at danger, although the train already in the block can proceed.

This arrangement is just one of many in which the present track devices can be used 35 for controlling traffic, and the illustration is to be taken as typical to make the invention better understood.

Figs. 7 and 8 show a modification in the controller 5' whose supplementary reservoirs 19' and 20' are not within the casing 6' but separate therefrom and mounted on a shelf 20^a. The valve 7' is also outside of the casing and supported on said shelf, and is of the spigot type to avoid leakage. The 40 valve 7' is rotatable to control the pressure fluid in the manner of the valve 7, suitable pipe connections being made. The valve operating piston 8' is movable in an independent cylinder 9' and the piston rod is connected to an arm 9^a of the valve 7' to turn it. This arrangement is preferable over that 45 shown in Fig. 1, because possible leakage under heavy pressure is avoided, and the parts are better suited for assemblage, re- 50 pairs, etc.

Having thus described the invention, what is claimed is:

1. Vehicle controlling apparatus embodying vehicle retarding and clearing magnetic members movably mounted for magnetic coöperation with other magnetic means when the vehicle passes points of a track where part of said apparatus is located, and operating means for alternately moving said members to operative position. 70

2. Vehicle controlling apparatus embodying vehicle retarding and clearing magnetic members movably mounted on the vehicle track for magnetically influencing magnetic vehicle carried retarding and clearing devices, respectively, and operating means for alternately moving said members to operative position. 75

3. Vehicle controlling apparatus embodying vehicle controlling magnetic members coöperable magnetically with other magnetic means when the vehicle passes points of the track where part of said apparatus is located, and an operative mounting for said members whereby they move alternately to operative position for different conditions. 80

4. Vehicle controlling apparatus embodying vehicle controlling magnetic members coöperable magnetically with corresponding magnetic means of a passing vehicle, and an operative mounting for said members on the track whereby they move alternately to operative position for different conditions. 90

5. Vehicle controlling apparatus including balanced magnetic vehicle controlling members alternately movable to operative position. 95

6. Vehicle controlling apparatus including vehicle controlling magnetic members for magnetically influencing retarding and clearing means on a passing vehicle, and a mounting on the track for said members to balance them for alternate movement to operative position. 100

7. Vehicle controlling apparatus including vehicle controlling magnetic members for coöperation with other magnetic means when the vehicle passes a point of its track where part of said apparatus is located, and a lever mounting carrying said members for alternate movement to operative position and so that they balance one another. 110

8. Vehicle controlling apparatus including vehicle controlling magnetic members on the track for magnetically influencing magnetic means on a passing vehicle, a lever mounting for said members whereby they balance one another and alternately move to operative position for different conditions, and means for operating said members. 120

9. Vehicle controlling apparatus including a set of three magnetic vehicle controlling members, one at the center of the track, and the others at opposite sides, and

means for mounting the last named members for simultaneous movement to and from operative position.

10. Vehicle controlling apparatus including a set of three magnetic vehicle controlling members, one at the center of the track, and the others at opposite sides, and means for mounting and operating said members whereby the first and second named ones move alternately to operative position.

11. Vehicle controlling apparatus including a set of three magnetic members for controlling magnetically responsive vehicle carried devices, one at the center of the track, and the others at opposite sides, a lever mounting for said members whereby they balance one another and alternately move to raised position, and means for operating said members.

12. Vehicle controlling apparatus embodying the combination with track semaphores, of movable magnetic members on the track operatively connected to said semaphores to move simultaneously therewith for controlling magnetic vehicle retarding and clearing means respectively, when the semaphores are at danger and clear positions.

13. Vehicle controlling apparatus embodying the combination with a track semaphore, of vehicle retarding and clearing magnetic members on the track operatively connected to the semaphore to alternately move to operative position, when the semaphore is moved to danger and clear positions, respectively.

14. Vehicle controlling apparatus embodying an armature device mounted on the track and movable to either clear or danger position, movable clear and danger electro-magnetic means on the vehicle selectively responsive to said device in its clear and danger positions, respectively, vehicle-controlling means operated by the movement of said clear and danger magnetic means, a non-magnetic casing on the track over said armature device to prevent obstruction of or interference with the movement thereof, and a non-magnetic casing on the vehicle inclosing said magnetic means to pass the aforesaid casing.

15. Vehicle controlling apparatus embodying movable armatures mounted on the track, a non-magnetic casing mounted on the track over said armatures, said casing having a depressed corrugation between said armatures, said armatures being movable at opposite sides of said corrugation, and electro-magnetic means carried by the vehicle to be attracted to said armatures.

16. Vehicle controlling apparatus embodying movable armatures mounted on the track, a non-magnetic casing mounted on the track over said armatures and having stiff-

ening means between said armatures, and electro-magnetic vehicle carried means movable over said casing to be attracted to said armatures.

17. Vehicle controlling apparatus embodying longitudinal armatures mounted for vertical movement on the track, a non-magnetic casing mounted on the track over said armatures, the top of said casing being depressed longitudinally between the armatures, and electro-magnetic vehicle carried means to be attracted to said armatures.

18. Vehicle controlling apparatus embodying longitudinal armatures mounted for vertical movement on the track, a non-magnetic so casing mounted on the track over said armatures having inclined ends beyond the ends of the armatures, the top of said casing being depressed longitudinally between the armatures from one inclined end of the casing to 85 the other.

19. Vehicle controlling means embodying a track device having an armature device movable alternately to clearing and danger positions, and a vehicle device having a controlling magnet device responsive to the armature device in either position thereof.

20. Vehicle controlling apparatus embodying electro-magnetic means carried by the vehicle and electrically energized and 95 movable to be attracted to an armature on the vehicle track, normally active means on the vehicle to retard the vehicle when said normally active means becomes inactive, and means whereby when the electro-magnetic 100 means is attracted to the armature and moved, the normally active means is rendered inactive.

21. Vehicle controlling apparatus embodying electro-magnetic means carried by the 105 vehicle and electrically energized and movable to be attracted to an armature on the vehicle track, a normally closed electrical circuit opened when said electro-magnetic means is so attracted and moved, electrical 110 means in said circuit to operate normally, and means whereby when the last named means stops, the vehicle is retarded.

22. Vehicle controlling means embodying track and vehicle devices, one device having 115 armature means and the other device magnetic means, said means coöperating magnetically and each being movable, one to active and inactive positions, and the other means being responsive to the aforesaid 120 means in either position to control the vehicle accordingly.

23. Vehicle controlling means embodying track and vehicle devices, one device having a plurality of movable magnetic means and 125 the other device having movable coöperating means for producing different conditions of the vehicle device.

24. Vehicle controlling means embodying a movable track device having a plurality of 130

magnetic means, and a movable vehicle device having responsive magnetic means for producing different conditions of the vehicle device.

- 5 25. Vehicle controlling apparatus embodying magnetic means on the vehicle magnetically responsive to magnetic means on the track for retarding the vehicle and maintaining said means in its responded condition, 70
 10 and magnetic means on the vehicle magnetically responsive to magnetic means on the track and controlling the first named magnetic means so that the first named magnetic means is restored when the last named magnetic means on the vehicle responds to its magnetic means on the track.

- 15 26. Vehicle controlling apparatus embodying movable electro-magnetic means on the vehicle to be attracted to an armature on the track, electrical means operable for retarding the vehicle when said means is deenergized, a source of electrical energy for normally energizing both of said means, and means whereby when said magnetic means is 80
 20 attracted to the armature the electrical energy is cut off from said electrical means.

- 25 27. Vehicle controlling apparatus embodying a vehicle controlling magnetic member movable in response to another magnetic means when the vehicle passes a point of the track where part of said apparatus is located, and a second magnetic member connected to the first named one and movable a greater distance therewith to be attracted and held 90
 30 to a magnetic object for maintaining both magnetic members in responded position.

- 35 28. Vehicle controlling apparatus including a pair of simultaneously movable vehicle controlling magnetic members, one of said 100
 40 members being movable to respond to magnetic means when the vehicle passes a point of the track where part of said apparatus is located, the other member being movable with said member through a greater distance 105
 45 to be brought into operation by such movement.

- 50 29. Vehicle controlling apparatus including a pair of simultaneously movable magnetic members carried by the vehicle for controlling its movement, one of said members being movable to respond to magnetic means on the track, the other member being movable with said member through a greater distance so as to be brought into operation by 110
 55 such movement.

- 60 30. Vehicle controlling apparatus embodying a magnetic member movable on a vehicle in response to magnetic means on the track, a second magnetic member movable with the first named magnetic member through a greater distance to be brought into attraction with a magnetic object, and vehicle controlling means controlled by the movement by the said members.

- 65 31. Vehicle controlling apparatus em-

bodying controlling means on the vehicle magnetically responsive to magnetic means on the track to retard the vehicle when said controlling means has responded, means for maintaining said controlling means in its responded condition, and means magnetically responsive to magnetic means on the track for releasing the controlling means under clear conditions.

32. Vehicle controlling apparatus embodying vehicle controlling means normally energized and magnetically responsive to magnetic means on the track to maintain vehicle retarding conditions, and clearing means magnetically responsive to magnetic means on the track for deenergizing said controlling means. 75

33. Vehicle controlling apparatus embodying armatures along the vehicle track movable to clear and danger positions, controlling means on the vehicle electrically energized to respond to said armatures in danger position for retarding the vehicle and maintaining such conditions, and clearing means on the vehicle magnetically responsive to the armatures in clear position and controlling said controlling means to let the vehicle proceed when the last named means responds. 85

34. Vehicle controlling apparatus embodying electro-magnetic controlling means on the vehicle magnetically responsive to magnetic means on the track for retarding the vehicle, electro-magnetic means for maintaining the first named electro-magnetic means in its responded condition, and clearing electro-magnetic means responsive to magnetic means on the track for deenergizing the aforesaid magnetic means of the vehicle. 95

35. Vehicle controlling apparatus including a source of electrical energy, electro-magnetic means normally energized from said source and movable to be attracted by an armature on the track, controlling means normally energized from said source and operable for retarding the vehicle when said controlling means is deenergized, electro-magnetic means normally energized from said source and operable when the aforesaid electro-magnetic means is moved to retain the first named electro-magnetic means and maintain vehicle retarding conditions, and other electro-magnetic means energized from said source when the first named electro-magnetic means is moved and movable in response to a clearing armature on the track for momentarily deenergizing the second named electro-magnetic means so as to restore normal conditions. 110

36. Vehicle controlling apparatus including movable magnetic means on the track, responsive movable magnetic means on the vehicle controlling its movement, and non-magnetic casings for both of said means to 120
 125 130

inclose same and permit uninterfered movement thereof.

37. Vehicle controlling apparatus embodying non-magnetic casings, one on the track and the other on the vehicle to pass the former, movable armatures in the track casing to move to and from active position within the track casing, and vehicle controlling means including movable magnets 10 within the vehicle casing.

38. Vehicle controlling apparatus including armatures on the roadbed movable to clear and danger positions alternately, and vehicle controlling means having movable magnets alternately responsive to said armatures.

39. Vehicle controlling apparatus embodying clear and danger track devices having plurality of means alternately movable to 20 operative position for magnetically influencing a vehicle device and producing different conditions thereof.

40. Vehicle controlling apparatus embodying a track device having a plurality of armatures alternately movable to clear and danger position to produce different conditions in a passing vehicle device.

41. Vehicle controlling apparatus including a double acting armature track device 30 actuated for either clear or danger positions, and responsively movable magnetic means on the vehicle controlling its movement according to the clear or danger position of the track device.

42. Vehicle controlling apparatus including automatic controlling means and signals on the vehicle, and a track device for operating same, said device consisting of movable armatures along the track alternately 40 set to danger and clear positions, and said controlling means including movable electro-magnets responsive to said armatures for either retarding or clearing the vehicle.

43. Vehicle controlling apparatus including armatures on the track movable to and from active position, electro-magnetic means on the vehicle movable in response to said armatures when in active position, a source of electrical energy for energizing said means, and means for retarding the vehicle brought into operation either by the movement of said means or the failure of electrical energy.

44. Vehicle controlling apparatus embodying a movable clear and danger armature device mounted on the track and movable to clear and danger positions alternately, a non-magnetic casing on the track inclosing said device to prevent the obstruction of or 60 interference with movements thereof, operating means controlling said device for moving it to different positions, said device being arranged to move to active danger position of itself should the controlling means fail or become disconnected from said de-

vice, electrically energized controlling means on the vehicle arranged to pass said armature device and having separate clear and danger devices magnetically and selectively responsive thereto in its clear and danger 70 position, respectively, and means to maintain the responsive condition of said controlling means after passing the armature device until track conditions change.

45. Vehicle controlling apparatus embodying 75 a track device having clear and danger armatures alternately movable to active position and arranged so that the danger armature moves to active position and the clear armatures to inactive position normally and 80 whenever free to do so, operating means for said device to move said armatures to their opposite position under clear conditions, and controlling means on the vehicle having clear and danger electro-magnets 85 responsive to said armatures for controlling the vehicle accordingly.

46. Vehicle controlling apparatus embodying 90 a track device having clear and danger armatures alternately movable to active position, and controlling means on the vehicle including a magnet responsive to the danger armature when in active position, a second magnet alternately responsive with the clear armature, vehicle retarding means 95 brought into operation when the first named magnet responds to the danger armature, and means for retaining such conditions until the second magnet responds.

47. Vehicle controlling apparatus embodying 100 in combination, an automatic block signal system, controlling means on the vehicle, and having electro-magnetic responsive means controlling same, and armatures on the track connected with said system to be 105 moved to active positions in harmony therewith for influencing said electro-magnetic responsive means accordingly, and provide a communicating medium between said system and controlling means.

48. Vehicle controlling apparatus embodying 110 in combination, an automatic block signal system having semaphores along the track, armatures mounted movably along the track and connected with said system 115 to be associated with the semaphores, said armatures being movable to provide a clear influence in one position and a danger influence in another position, and controlling means on the vehicle having electro-magnetic responsive means to pass said armatures and operable to respond for clear and danger conditions according to the position of the armatures.

49. Vehicle controlling apparatus embodying 125 in combination, an automatic block signal system having semaphores along the track, controlling means on the vehicle having clear and danger electro-magnets movable for controlling the vehicle accordingly,

means for retaining train retarding conditions, when the danger magnet is moved, until the clear magnet is moved, and track devices along the track and each including
5 clear and danger armatures alternately movable to active position for influencing the clear and danger magnets, and connected with said system in association with the semaphores so that the danger armatures
10 will be in active position unless the sema-

phores are in clear position and the connections operative to move the clear and danger armatures to active and inactive positions, respectively.

This specification signed and witnessed 15 this 2 day of February, 1918.

ALFRED L. RUTHVEN.
